HOSE SUPPORTER

Victoria G. Corel, San Leandro, Calif.

Application October 18, 1938, Serial No. 235,595

4 Claims. (Cl. 24—245)

This invention relates to improvements in hose supporters and, more particularly, to an improved clasp for engaging the hose.

Among the objects of the invention is to provide a hose supporter clasp which, when assembled on the stocking, will be substantially planar in form and of minimum thickness so that it may be sat on without discomfort and, further, will be invisible through the clothing of the wearer.

Another object is to distribute the stresses in the stocking occasioned by the supporter over a relatively large area so as to minimize runs and tears.

Another object is to avoid sagging of the stocking above the clasp.

Another object is to render the structure of the clasp such that it may be produced in quantity with economy of labor and materials.

Other objects and advantages appear as this description progresses.

In this specification and the accompanying drawing, the invention is disclosed in its preferred forms. It is to be understood, however, that it may be embodied in other modifications within the purview of the claims following the description.

In the one sheet of the drawing:

Fig. 1 is a side elevation of a hose supporter including a clasp constructed in accordance with the present invention applied to a stocking.

Fig. 2 is an enlarged, vertical section of the same taken along the line II—II in Fig. 1.

Fig. 3 is a plane view of the blank from which the button member of the clasp is formed.

Fig. 4 is a similar view of the same assembled on the elastic tape forming the body of the supporter.

Fig. 5 is a vertical section of the same.

Fig. 6 is a plane view of the blank from which the eye member of the clasp is formed.

Fig. 7 is a similar view of the same assembled.

Fig. 8 is a vertical section of the same.

Fig. 9 is a vertical section of a modified form of eye member.

In detail, the construction illustrated in the drawing comprises the blank from which the button member 1 of the clasp is formed, which is preferably of thin sheet metal of a thickness of one hundredth (.010) of an inch, although this thickness may be widely varied to meet conditions. The metal should be thin enough to achieve minimal thickness of the assembled clasp and yet must be of a sufficient thickness to insure against the edges of the button member severing or otherwise damaging the knitted stocking.

The body 1 of the button has the wing 2 extending therefrom and adapted to be bent on the line 3 back over the body 1. The outer edge of the wing 2 has the serrate teeth 4 provided thereon at intervals. These teeth are bent over at right angles to the wing so they are disposed toward the body 1 of the button when the wing is folded back on the line 3. The body of the button has the series of triangular holes 5 therein which are adapted to receive the teeth 4 when the button is assembled.

In assembling the button, the end of the elastic tape 6 is inserted between the body 1 and the wing 2. The wing 2 is then forced toward the body 1 by a suitable pressure member, which causes the teeth 4 to penetrate through the tape 6 and enter the series of triangular holes 5. The end of the tape 6 is thus fixed between the body 1 and the bent over wing 2, being held against withdrawal by its impalement on the teeth 4.

When thus assembled on the elastic tape 6, the button is substantially planar in form with parallel side and semi-circular ends. The tape 6 is of slightly less width than the length of the button 1, although this is not essential.

The eye member 7 of the clasp is formed from the blank shown in Fig. 6 and is of sheet metal similar to that composing the button member 1. It has the opening 8 therein with the integral wing 9 extending from the inner side of the opening. The wing is adapted to be folded back on the line 10 over the extension 11 of the eye member. When the wing member is thus folded back, the opening 8 is left with smooth margins and is of a shape roughly corresponding to that of the button member 1. However, the opening 8 is of materially less width, as later described.

The wing 9 has the teeth 12 in its outer edge which are arranged to be bent at right angles to the wing so as to enter the series of holes 13 provided in the extension 11 when the eye member is assembled. The eye member is assembled on the opposite end of the elastic tape 6 in substantially the manner of the button member 1 by impaling the tape on the teeth 12.

The central portion of the tape 6 runs through the loop 14 which has the supporting tape or tapes 15 connected to a conventional foundation garment, girdle, or "garter belt" by any of the means well known in this art. If desired, the button and eye members of the present clasp could obviously be mounted on separate tapes without departing from the spirit of the invention.

In engaging the clasp, the button 1 is inserted

within the stocking and the eye member 7 positioned exterior to the stocking adjacent the button 1. The button and the overlying thickness x of the stocking are inserted completely through 5 the opening 8 in the eye member. The button 1 lies against the tape 6 in the position shown in Fig. 5 during its passage through the opening 8. After the button 1 has been passed completely through this opening, its upper portion is swung 10 away from the adjacent section of the tape 6. The tape is then pulled backwardly through the opening 8 until the margins of the button 1 are brought into planar engagement with the surface of the eye member 7, as in Fig. 2. The opening 15 8, being of less width than the button 1, as hereinbefore described, prevents the button slipping through the opening.

The upward thrust of the tape 6 relative to the stocking x moves the button 1 upwardly 20 until the junction of the tape 6 with the button 1 at the teeth 4 is brought into engagement with the bend 10 of the wing 9 at the upper margin of the opening 8. It is at this point that a large fraction of the supporting stress is applied to the stocking. The diameter of the bend 25 10, being wide in comparison with the thickness of the sheet metal composing the eye, safeguards against undue wear on the stocking.

The portion of the stocking x above the assembled clasp is confined between the two depending sides of the tape 6. The thinness of the clasp brings these ends of the tape into close proximity with each other. The stocking is thereby frictionally engaged therebetween, thus preventing the portion of the stocking above the clasp from sagging, to the discomfort of the wearer.

When it is desired to disengage the clasp, the button 1 is pulled outwardly from the eye member 7. It is then swung so as to lie co-planar with the end of the tape 6 to which it is attached. The tape 6 is retracted through the opening 8, drawing the button 1 with it. This frees the stocking x , which may then be removed.

45 In the modified form shown in Fig. 9, the button member has the auxiliary wing member $2x$ which is bent back at $3x$ over the body 1, thus making the button member of more nearly uniform thickness throughout. When the clasp is engaged, the modified button member will then lie substantially parallel with the eye member 50 of the clasp. (Compare with Fig. 2.)

Having thus described the invention, what I claim and desire to secure by Letters Patent is:

1. In a hose supporter having a depending tape end; a clasp member having a body with a series of holes therethrough, an integral wing 5 adapted to be bent back over the body of said clasp member and a series of teeth in the edge of said wing and angularly disposed thereto and adapted to enter said series of holes whereby to impale said tape end extending between the 10 body of said clasp member and said wing.

2. In a hose supporter having a depending tape end; a clasp including an eye member having an opening therethrough and a horizontally aligned series of holes in its upper portion, an 15 integral wing extending from the upper side of said opening and adapted to be bent back over the body of said eye member, and a series of teeth on the edge of said wing and angularly disposed thereto and adapted to enter said holes 20 in the body of said eye member, whereby to impale the tape end extending between the body of said eye member and said wing.

3. In a hose supporter having a depending tape 25 end, a clasp including an eye member of relatively thin sheet metal having an opening therethrough and a series of holes lateral to said opening, an integral wing extending from the side nearest said holes and adapted to be bent back 30 over the body of said eye member, and a series of serrate teeth on the edge of said wing and adapted to enter said series of holes, whereby to impale the tape end extending between the body of said eye member and said wing.

4. In a hose supporter having a depending elastic tape end; a clasp having an eye member composed of sheet metal of less thickness than said elastic tape and having an opening therethrough and a series of holes lateral to said opening, an integral wing extending from the side 40 of said opening nearest said holes and adapted to be bent back over the body of said eye member, and a series of serrate teeth in the edge of said wing and disposed at substantially right 45 angles thereto and adapted to enter said series of holes in the body of said eye member, whereby to impale the tape end extending between said eye member and said wing.
